By Arthur F. Durand
Atty.

UNITED STATES PATENT OFFICE

EDWARD CRAIG, OF ST. JOSEPH, MICHIGAN; THE COMMERCIAL NATIONAL BANK, EXECUTOR OF THE ESTATE OF SAID EDWARD CRAIG, DECEASED, ASSIGNOR TO SARANAC MACHINE COMPANY, OF BENTON HARBOR, MICHIGAN, A CORPORATION OF MICHIGAN

WIREBOUND BARREL AND METHOD OF MANUFACTURE THEREOF

Application filed February 7, 1927. Serial No. 166,434.

This invention relates to the manufacture of wire bound barrels, and more particularly to the manufacture of barrels of this kind having both bilge and end hoops.

Generally stated, one object of the invention is to provide a strong and serviceable construction of wire-bound barrel, in which the encircling binding wires are applied in a manner to give the barrel strength and serviceability, and in which the construction is such that barrels of this kind may be manufactured at a comparatively low cost of production.

Another object is to provide a method of construction of wire-bound barrels of this kind, and a process or method of assembly thereof, of such a character that the manufacture of the barrels will be facilitated, and in a manner to permit quantity production thereof at a reasonable cost and in a manner to insure barrels which will be satisfactory to the users.

To these and other useful ends, the invention consists in the matters hereinafter set forth and claimed, and shown in the accompanying drawings, in which,—

Fig. 1 is a side elevation of a wire-bound barrel embodying the principles of the invention, showing a portion thereof in section.

Fig. 2 is a cross section on line 2—2 in Fig. 1.

Fig. 3 is an enlarged, detail, sectional view illustrating the method of driving the staples to secure two hoops and a wire in position at the bottom end of the barrel.

As thus illustrated, the barrel comprises staves 1 of any suitable character, such as wood, and bent into the desired shape, as shown. The barrel may have a wood hoop 2 for the top end thereof, and preferably has the two bilge hoops 3 and 4, the hoop 3 being of wood or sheet or strap metal, and the hoop 4 being of wire. The outside, bottom hoop 5 may be of wood or metal, and is preferably reinforced with an outer hoop 6 of wire, as shown. The inside, bottom hoop 7 forms the inner rim of the bottom end of the barrel, and is inserted as shown to hold the bottom 8 of the barrel in place. Staples 9 are driven crosswise of the wire 6, with one leg

10 of the staple penetrating through the hoop 5 and through the staves 1 into the bottom 8, as shown in Fig. 3 of the drawings. The other leg 11 of the staple is inserted through the hoop 5 and through the stave 1 and through the inner hoop 7 previously mentioned, and clinched on the inner surface of this hoop 7, the latter being formed with a bevel or slant in cross section, as shown. Staples 12 are driven through the hoop 3 to hold this hoop in place, and staples 13 are driven crosswise of the wire 4 to hold this hoop in place. The two wires are preferably attached at their starting ends by staples 14, as shown, and the other ends of these wires 15 are then brought around and caused to overlap the starting ends, the overlap then being straddled by the staples 9 and 13, as shown.

Obviously, in order to obtain the construction shown and described, and especially the stapling of the overlap ends of the wires in place, the process or method comprises the assembly of separately formed staves in barrel form, with the edges of the staves held tightly together throughout the length of each stave, and thereafter stapling a plurality of outside bilge hoops and an outside bottom hoop in place, upon the said staves, thereby forming a bilge barrel; and, of course, it is also a part of the process or method that the fastening of the bottom head 8 in place is accomplished simultaneously with the fastening of the bottom hoop in place; and, furthermore, before the various staples can be driven, the staves must be held in place by placing the hoops 2 and 5 in position as shown, and thereafter the stapling operations are performed as shown and described.

Any suitable means can be employed, of course, for setting up the staves and flat end hoops. Machinery or instrumentalities of any known or suitable character can be employed for this purpose, and thereafter the stapling operations can be performed by machinery of the kind shown and described in co-pending application of Edward Craig, Serial No. 166,435, filed February 7, 1927, of which latter this application may be regarded as a division.

Without disclaiming anything, and without prejudice to any novelty disclosed, what I claim as my invention is:

1. In barrel construction, the combination of staves, a bottom head, an outside bottom hoop and staples extending through the hoop and staves, with the staple heads extending crosswise of the hoop, one leg of each staple extending into the bottom head, and the other leg of each staple being clinched with its end portion exposed adjacent one side of said head.
2. A structure as specified in claim 1, in combination with an inside bottom hoop held in place against the outside of the bottom by the clinched legs of the staples.
3. A structure as specified in claim 1, comprising a wire hoop superposed upon said outside bottom hoop and held in place by said staple heads.
4. A structure as specified in claim 1, the said clinched portions of the staples being exposed on the barrel surface between said head and the end edges of the staves.
5. In barrel construction, the combination of separately formed staves tightly engaging at their side edges throughout the length of each stave, a plurality of bilge hoops and a bottom hoop, at least one bilge hoop comprising an encircling wire with overlapping end portions disposed side by side against the barrel, forming a straight overlap, and staples securing said hoops and overlap in place, forming a bilge barrel, some of said staples straddling only one end portion of said wire, and some of said staples straddling both end portions of the wire, holding the two end portions tight together, whereby one end portion may be attached first and the other afterward to provide an anchor for one end while the wire is being wound around the barrel, the staples for the bottom hoop having one leg of each staple clinched, and an inside bottom hoop held in place by said clinched portions of the staples, together with a bottom head held in place by said inside bottom hoop, and the unclinched other legs of said staple.
6. In barrel construction, the combination of staves, a bottom head, an outside bottom hoop and staples extending through the hoop and staves, one leg of each staple extending into the bottom head, and the other leg of each staple being clinched adjacent one side of said head, in combination with an inside bottom hoop held in place against the outside of the bottom by the clinched legs of the staples.
7. In barrel construction, the combination of separately formed staves tightly engaging at their side edges throughout the length of each stave, a plurality of bilge hoops and a bottom hoop, at least one bilge hoop comprising an encircling wire with overlapping end portions disposed side by side against

the barrel, forming a straight overlap, and staples securing said hoops in place, forming a bilge barrel, the staples for the bottom hoop having one leg of each staple clinched, and an inside bottom hoop held in place by said clinched portions of the staples, together with a bottom head held in place by said inside bottom hoop and the unclinched other legs of said staples.

Specification signed this 31st day of Jan., 1927.

EDWARD CRAIG.
